HINGE FOR WINDOWS

Einar Särenholm, Eskilstuna, Sweden, assignor
to Svartviks Aktiebolag, Sundsvall, Sweden, a
corporation of Sweden

Application August 6, 1947, Serial No. 766,713
In Sweden June 2, 1947

5 Claims. (Cl. 16—140)

1

The present invention refers to pivot hinges for windows, particularly windows having a casement (or casements) swingable approximately at its middle portion about a horizontal axis of rotation, wherein at least a portion of the swinging movement of the casement from its closed position takes place with a braking effect. The object of the invention is to render possible an effective braking effect without resorting to springs or the like. In a previously proposed construction of pivot hinges of the type in consideration, the casement is carried, during the outward swing from a certain small opening position, designated as the quick-ventilation position, by a movable arcuate braking surface resting on a corresponding arcuate braking surface, which is stationary during said swinging movement. With that construction, the weight of the casement or casements will be transmitted directly onto the stationary braking surface, on which the casements may be said to be suspended during the outward swinging movement. With that construction, the available braking power can never be greater than the weight of the casements, which has been found to be insufficient for most purposes.

In comparison with the previously suggested construction, an improvement has been evolved, according to the present invention, to attain an efficient braking effect, said improvement consisting in the provision of a lever to transmit the braking power originating from the weight of the casement to a braking surface in such manner that the braking power is increased by a leverage effect.

The arrangement may be devised so that the braking effect manifests itself practically during the whole of the opening movement or closing movement of the window, but since it is generally desirable that the window shall permit of being rapidly, and perhaps, automatically swung out into the quick-ventilation position from its closed position, the hinge is rather constructed so that the braking effect commences to act only when the casement approaches the quick-ventilation position in being swung out.

The invention is substantially, but not exclusively, intended to be applied to pivot hinges having a pivoted intermediate member, which facilitates the outward swinging movement, first about one and then about the other of two axes of rotation located beside one another, and in this application, the lever, which is provided with a braking surface, is pivotally mounted on the pivoted intermediate member, which is swingable in known manner on a pin of a fitting secured to

2

the window casement. A second braking surface arranged for cooperation with said first-mentioned surface is formed here on a fitting secured to the casement, the lever being arranged to be moved with its braking surface against the braking surface of the casement fitting by reason of the movement of the casement and the link-shaped intermediate member relatively to the casement during the first portion of the outward swinging movement of the casement from its closed position.

Further features characteristic of the invention and advantages inherent therein will appear from the following description and are illustrated in the accompanying drawings in which:

Figure 1 is a side elevation of the hinge and a part of the frame,

Fig. 2 is a side elevation similar to Fig. 1 with the parts in different positions,

Fig. 3 is a side elevation similar to Figs. 1 and 2 with the parts in different positions,

Fig. 4 is a side view of a detail,

Fig. 5 is a sectional view of a detail taken on line 5—5 of Fig. 2, and

Figs. 6 to 9 are top plan views of the frame fitting, intermediate member, lever and casement fitting respectively.

The hinge arrangement is shown in vertical projection in Figs. 1-3 of the drawing, viewed on the side of the casement facing the middle portion of the window opening, the parts of the same secured to the casement being indicated by chain-dotted lines. Fig. 1 corresponds to the closed position of the window, Fig. 2 to the quick-ventilation position, and Fig. 3 to a larger opening position, wherein the braking effect manifests itself.

In the drawings, 1 designates the frame (only a portion of the one vertical frame member being indicated), and 2 denotes one, for instance the inner one, of the two interconnected casements, which are suspended in the frame by means of the hinge contrivance in accordance with the invention. The second casement, for instance the outer one, is designated by 3.

Secured to the insides of the two vertical frame pieces of the window are fittings 4 each provided with an inwardly protruding fixed pin 5 having a segment-shaped linked intermediate member 6 mounted thereon. The fittings 4 are also each provided with a fixed stop abutment 7 approached by the lower edge of the intermediate member 6 at the outward swinging into the quick-ventilation position (Fig. 2). According to the invention, a lever 9 is pivotally mounted on

a pin 8 on the intermediate member 6, said lever being provided with a flange 19 and a braking coating 11 to form one of the braking surfaces of the braking device. The other braking surface is formed by an arcuate flange 12 on a fitting 14 secured to the casement 2. Furthermore, the fitting 14 is provided with a pin 15 projecting into a guide in the form of an edge recess or pocket 16 in the link-shaped intermediate member 6. The bottom of the pocket 16 is formed by a flange 17 and the pin 15 is supported pivotally on said bottom. The pins 15 of the hinges at both sides of the window form pivots, about which the casements are swung outwardly from the quick-ventilation position to a greater opening position. Furthermore, there is provided a carrier pin 18 on the fitting 14, said pin being withdrawn during this movement from the quick-ventilation position out of the edge recess while being again, when the casements are swung back toward the position of closure, introduced into the edge recess so as to abut against the flange 17, thereby being then capable of moving the intermediate member 6, along therewith in the turning of the casements about the pin 5, during the movement from the quick-ventilation position to the position of complete closure.

To set the braking surface of the lever against the braking surface of the casement fitting, there is provided, preferably on the frame fitting 4, a guide pin 19 cooperating with a cam surface 20 on the lever 9. The position of the guide pin 19 and of the cam surface 20 is so designed relatively to the positions of the pivot pin 5 of the intermediate member on the frame fitting 4 and the bearing pin 8 of the lever on the intermediate member, so that the braking surface of the lever is set against the braking surface of the casement fitting to effect a leverage. The guide pin 19 extends through a slit 21 in the link-shaped intermediate member so as to be permitted to be brought into engagement with the lever 9 mounted on the opposite side. The slit also confines the mobility of the intermediate member relatively to the frame, so that the casements are prevented, at the beginning of a closing movement, from being raised by reason of the turning facilities of the intermediate member and the effect of the braking device.

The mode of operation of the arrangement described is as follows:

In the position of closure shown in Fig. 1, the intermediate member 6 is swung upwardly, so that the guide pin 19 is located at the lower end of the slit 21, while the part of the cam surface 20 adjacent to the pivot 8 for the lever 9 is bearing against the guide pin 19. When the window is to be opened from the position of closure, the casements first turn about an axis of rotation determined by the fixed pins 5 on both frame pieces. The intermediate member 6 is thus carried along in the movement of the casements, as if it were integral therewith. During this first movement only the bearing friction at the pins 5 is active as a resistance to the movement in the example shown, by reason of which the outward swinging is effected readily and may be attained, if desired, by suitably placing the center of gravity of the casements relatively to the axis of rotation determined by the pins 5. During this outward swinging movement, which generally only comprises a certain small angle, the lower edge of the intermediate member 6 approaches the fixed stop abutment 7. The bearing pin 8 for the lever 9 is also carried along in the movement,

whereas the outer end of the lever provided with the braking coating 11 has a movement imparted thereto, which is determined by the engagement of the cam surface 20 with the fixed guide pin 19 and the sliding movement of said surface 20 on said pin 19. The movement results in the braking coating 11 moving inwardly toward and setting against the convex side of the arcuate flange 12. It is generally preferred to choose the position of the guide pin 19 so that the braking coating is completely set, before the lower edge of the intermediate member hits the stop abutment 7.

The weight of the casements, which influences the intermediate member 6 by means of the pin 15 supported by the flange 17, causes a downwardly directed force acting at the center of the pin 8. This force causes, in turn, a braking effect which is related to the downwardly directed force in comparison as the moment arm of the latter with respect to the center of the pin 5 is related to the moment arm of the braking force with respect to the same center. Since the moment force is active very much nearer to the center of rotation than the downwardly directed force, and consequently has a substantially smaller moment arm than the latter, it will be correspondingly greater. The leverage thus provides for an increase of the available braking power in comparison with that instance when the casements are supported directly by braking surfaces. This effect manifests itself during outward swinging movement of the casements which are then turning about the pins 15 as long as the braking surface of the lever engages the flange 12, when the latter is turning, the movement taking place consequently at braking. By a suitable selection of the leverage, a braking effect of the desired magnitude can be attained, so that the casements may be effectively retained, during that part of the movement in which the braking effect manifests itself, in an arbitrary opening position, to which they have been adjusted.

The invention may be advantageously applied to such windows which are provided with closing means permitting a fine adjustment of the opening movement during the very first part thereof, and where the casements, on having been released from the closing device, are caused to swing out automatically into the quick-ventilation position.

The braking surface of the flange 12 is preferably shaped on a circular arc with the center of the pin 15 at its center, but it may occur in certain cases that the flange is arranged eccentrically, in part at least, in a manner such that the braking effect will be varied accordingly in a certain manner during the opening and closing movements. It may be found to be advantageous to provide for an increased braking power toward the end of the opening movement as a compensation for the reduction of the braking surface setting in when the braking surface of the lever commences to leave the end of the flange.

Further modifications of the embodiments shown may be evolved, without the scope of the invention being exceeded thereby.

A special advantage inherent in the hinge described is that the window becomes less sensitive to varying positions of the center of gravity of the casements relatively to the axes of rotation of the casements. Thus the vertical line through the center of gravity of the casements,

which is generally situated above the axes of rotation, may fall, in the position where the brake commences to be effective at the outward swinging of the casements, on or outside the center line of the pins 15 (thus not between the center lines of the pins 15 and 5), inasmuch as the turning moment then manifesting itself, which tends to swing the casements with their upper edges downwardly, is outweighed by the braking effect then setting in.

What I claim is:

1. A pivot hinge for windows having a frame and a casement pivoted to the frame about horizontal axes, comprising a casement fitting, a frame fitting, a link member pivoted to the frame fitting and carrying the casement fitting, the fitting carried by the link member being formed with a brake surface, a lever pivoted to said link member and having a brake surface for cooperation with said brake surface of the fitting, and means to move said lever relatively to the link member to bring its braking surface towards and into contact with the braking surfaces of the fitting as a result of the movement of the casement and the link member relatively to the frame during the first portion of the outward swinging movement of the casement from the position of closure.

2. A pivot hinge for windows having a frame and a casement pivoted to the frame about horizontal axes, comprising a casement fitting, a frame fitting, an intermediate member pivoted to one of said fittings and carrying the other fitting, the last-mentioned fitting being formed with a brake surface, a lever pivoted to said intermediate member and having a brake surface for cooperation with said brake surface of the said other fitting, a cam surface on the lever between the ends thereof spaced from its pivot on the link member and a stationary pin engaging said cam surface for tightening the braking surface of the lever against the braking surface of the fitting as a result of the movement of the casement and the intermediate member relatively to the frame during the first portion of the outward swinging movement of the casement from the position of closure.

3. A pivot hinge for windows having a frame and a casement pivoted to the frame about horizontal axes, comprising a frame fitting, an inter-

mediate member pivoted to the frame fitting, a casement fitting formed with an arcuate brake surface with means for suspending the casement on the intermediate member, a lever pivoted to said intermediate member and having a brake surface for cooperation with said arcuate brake surface, means actuating the lever for engaging the brake surface thereof with the arcuate brake surface as a result of a swinging movement of the intermediate member relatively to the frame fitting during the first opening movement of the window casement from its closed position, and a stop for ultimately limiting the swinging movement to a predetermined value.

4. A pivot hinge for windows having a frame and a casement pivoted to the frame about horizontal axes, comprising a fitting mounted on the casement and having a brake surface, a second fitting mounted on the frame, a lever having a brake surface for cooperation with the brake surface of said casement fitting, means connecting said frame fitting with said lever and carrying the weight of the casement, the lever being pivoted to said connecting means, and stationary abutment means on the second fitting to be engaged by said lever between the ends of the lever as a result of an opening movement of the casement, whereby the braking force between said surfaces will be increased by a leverage effect.

5. A pivot hinge as claimed in claim 4, in which the brake surface of the lever is adapted to cooperate with the convex side of an arcuate flange formed with the brake surface of the casement fitting.
